UNITED STATES PATENT OFFICE.

GUSTAV W. EHRHARDT AND MERRIAN SCHIAVON, OF CHICAGO, ILLINOIS.

PRESS-PLATE.

1,129,181.

Specification of Letters Patent. Patented Feb. 23, 1915.

Application filed June 24, 1913. Serial No. 775,580.

To all whom it may concern:

Be it known that we, GUSTAV W. EHRHARDT and MERRIAN SCHIAVON, citizens of the United States, residing at Chicago, in the county of Cook, State of Illinois, have invented certain new and useful Improvements in Press-Plates; and we do hereby declare the following to be a full, clear, and exact description of the invention, such as will enable others skilled in the art to which it appertains to make and use the same.

The present invention is directed to improvements in press plates adapted for use in connection with printing presses for embossing, and has for its object to so construct a plate of this type that the same can be easily handled.

A further object of the invention is to provide a plate of this type which is electrically heated, and one which is exceedingly simple in construction, durable and efficient in operation.

With these and other objects in view, this invention resides in the novel features of construction, formation, combination and arrangement of parts to be hereinafter more fully described, claimed and illustrated in the accompanying drawing, in which:

Figure 1 is a plan view of the device. Fig. 2 is a similar view with top plate removed. Fig. 3 is a sectional view on line 3—3 of Fig. 1. Fig. 4 is an end view of the device.

Referring to the drawing, the numeral 1 designates a metallic casing which is preferably rectangular in shape and consists of sides 2, ends 3 and top and bottom plates 4 and 5, respectively. Arranged transversely, and spaced apart is a plurality of porcelain tubes 6, said tubes having their ends engaging the sides 2. The sides 2, ends 3 and top and bottom plates 4 and 5 are lined with

asbestos sheets 7, which prevent injury to the casing by heat from the coils.

Heating coils 8 encircle the tubes 6 and 43 are electrically connected by wires 9. The terminals of the outermost coils 8 are connected to a plug 10, which is carried by one of the end plates 3 and is adapted to be attached to a suitable source of electrical energy, which when passed through the coils will effectively heat the device.

Passing through the sides 2 of the casing 1 are screws 11, which serve to brace the casing.

By employing the members 6 in tubular form and engaging their ends against the sides 2 so as to seal the same, we provide for dead air spaces therein, which because of their non-conducting quality will cause the heat generated in the coils 8 to radiate outward and thus contribute to the more effective operation of the device.

What is claimed is:

A press plate for printing presses, consisting of a casing comprising sides and ends, and top and bottom plates connected thereto, a plurality of porcelain tubes arranged transversely of the casing and spaced apart with their ends engaged in and closed by the sides of the casing, a non-conducting lining for the casing, heating coils encircling said tubes and connected in series, said coils and tubes filling the space vertically in said casing, and a plug mounted in one end of the casing for receiving the terminals of the coils.

In testimony whereof, we affix our signatures in the presence of two witnesses.

GUSTAV W. EHRHARDT.
MERRIAN SCHIAVON.
